Patented Mar. 6, 1962

192,336

SLIDE PROJECTOR

Raymond A. Grosso, Royal Oak, Mich., assignor to Sylvania Electric Products Inc., a corporation of Delaware

Filed Jan. 17, 1961, Ser. No. 63,593

Term of patent 14 years

(Cl. D61—1)

FIG. 1

FIG. 2

FIG. 3

FIG. 4

FIGURE 1 is a front perspective view of a slide projector, in closed condition, showing my new design;

FIGURE 2 is a front elevational view of the same, with the front cover in open condition;

FIGURE 3 is a rear perspective view of the same, in closed condition; and

FIGURE 4 is a rear elevational view of the same, with the rear cover in open condition.

I claim:

The ornamental design for a slide projector, substantially as shown.
